STANDARD VARNISH WORKS, OF NEW YORK, N. Y., A CORPORATION OF NEW YORK.

LIQUID-COATING MACHINE.

1,014,282.

Specification of Letters Patent.

Patented Jan. 9, 1912.

Application filed March 19, 1908. Serial No. 422,023.

To all whom it may concern:

Be it known that we, REME A. BEAUSEJOUR, a subject of the Crown of Great Britain, and resident of the borough of Brooklyn, in the city and State of New York, and GUSTAV DRUBEL, a citizen of the United States, and resident of the borough of Richmond, in the city and State of New York, have invented a new and useful Improvement 5 in Liquid-Coating Machines, of which the following is a specification.

The object of our invention is to provide certain improvements in an article dipping apparatus whereby a common fluid actuated means is employed for raising and lowering a pair of article holders, said means comprising a cylinder, a piston and means for accurately adjusting the position of the cylinder with respect to the tanks in which 10 the article holders are dipped and for holding the cylinder in such adjusted position.

A further object is to provide an article dipping apparatus of the above character in which the piston of the fluid actuated 15 means forms the sole support for the article holders.

A practical embodiment of this invention is represented in the accompanying drawings in which—

Figure 1 represents in perspective the improved article dipping apparatus, the parts being shown in full lines in their lowered position and in dotted lines partially broken away in their raised position, one of the 35 article holders being shown in dotted lines released from its supporting bracket and the other article holder being shown secured to the supporting bracket. Figs. 2 and 3 represent detail perspective views showing 40 the manner of removably securing the article holders to the supporting bracket.

The liquid containing tanks are denoted by 1. Between these tanks there is located the cylinder 2 of a fluid actuated device the 45 piston of which is denoted by 3. The piston rod is denoted by 4 and it extends upwardly through the top cylinder head 5. An article holder supporting bracket 6 is rigidly secured to the piston rod 4 by set 50 screws 7 located in the vertical tubular extension 8 of the said bracket. Arms 9 extend laterally from the base of the bracket 6 and truss rods 10 lead from the top of the tubular extension 8 to the ends of the 55 bracket arms 9. Article holders 11 are re-

movably secured to the bracket arms 9, in the present instance by providing a hook latch 12 carried by one of the top cross bars 13 of each article holder, arranged to pass through a hole 14 in the bracket arm 9. 60 These upper cross bars 13 are provided with clips 15 for engaging the opposite sides of the arm 9 for maintaining the article holder in position. Each article holder is provided with bars 16, 17 depending from one of the top cross bars 13, the lower ends of which bars are connected by a bottom rack 18. This bottom rack 18 is arranged to support the bottom of the article 19 to be dipped. The top of said article is held in 70 position by one of a series of spring clips 20 carried by a rod 21. This rod 21 is made vertically adjustable by providing the holder with straps 22, 23, extending from one of the top cross bars 13 to the depending bars 16, 17, at points a distance below said cross bar 13, and providing the said straps 22, 23, with holes for the reception of pins 24, 25, passing through the ends of the bar 21 and through the holes in the 80 said straps. Means are provided for accurately adjusting the position of the cylinder 2 between the tanks 1, which means in the present instance comprise a frame 26 surrounding the cylinder 2, said frame having 85 adjusting screws 27 leading through the frame into engagement with the sides of the said cylinder.

The fluid inlet pipe is denoted by 28. The pressure regulator 29 is located in this pipe 90 and also a pressure gage 30. This inlet pipe 28 is provided with a branch pipe 31 leading to the top of the cylinder 2 and a branch pipe 32 leading to the bottom of the said cylinder. The fluid outlet pipe 33 is connected to the branch pipe 31 through a pipe 34 having a manually operated valve 35 therein. This outlet pipe 33 is also connected to the inlet branch pipe 32 through a pipe 36 having a manually operated valve 95 100 37 therein. A manually operated valve 38 is located in the branch inlet pipe 32 and a manually operated valve 39 is located in the main inlet pipe 28.

In operation, supposing the parts to be 105 in the position shown in full lines Fig. 1. The valves 37 and 39 are closed and the valves 38 and 35 are open. This will admit the motive fluid to the underside of the piston 3 and open the upper side of the said 110

piston to the fluid outlet. This will cause the supporting bracket 6 with its article holders secured thereto to be raised, thus lifting the articles gradually and evenly 5 out of the coating liquid within the tanks 1. After the bracket 6 has been raised to the desired point, the article holders may be detached therefrom and other holders may be secured to the said bracket in position to 10 be lowered with the articles therein into the tanks. To produce this latter movement the valves 35 and 38 are closed and the valves 37 and 39 opened. This will permit the motive fluid to enter the space above the piston 15 3 and open the space beneath the said piston to the outlet 33. This arrangement will cause the articles to be lowered into the tanks. After the articles have been left in the tanks a predetermined time, they may in 20 turn be lifted out of the tanks in the manner hereinbefore described.

It will be seen from the above description that the articles are lifted out of the tanks by fluid actuated means, thus insuring a 25 much more even and smooth movement than has heretofore been possible where mechanical or manual means have been employed. There has always been more or less backlash in connection with mechanically and 30 manually operated devices, resulting in a more or less uneven coating of the article as it is withdrawn from the tank. The means herein set forth insures an absolutely homogeneous coating of the article which will not 35 be disturbed by the withdrawal of the article from the tank. This is extremely important, especially when the articles treated are of a nature which require utmost accuracy in the coating of the same, such for instance, 40 as parts of a piano casing. Furthermore, means are shown for very readily removing one holder and substituting another holder when the supporting bracket is in its raised position.

45 What we claim is:

1. An article dipping apparatus includ-

ing a pair of liquid containing tanks, article holders, fluid actuated means for raising and lowering the holders, comprising a cylinder located between the tanks, its piston, 50 means for controlling the admission and escape of the fluid to and from the opposite sides of the piston and means for accurately adjusting the position of the cylinder with respect to the tanks and holding it in such 55 position.

2. An article dipping apparatus including a pair of liquid containing tanks, article holders, fluid actuated means for raising and lowering the holders comprising a cylinder located between the tanks, its piston, 60 means for controlling the admission and escape of the fluid to and from the opposite sides of the piston, and means for accurately adjusting the position of the cylinder 65 with respect to the tanks and holding it in such position comprising a frame fixed to the tanks and surrounding the cylinder, and adjusting screws mounted in said frame and fitted to engage the cylinder. 70

3. An article dipping apparatus including a pair of liquid containing tanks, article holders and fluid actuated means for raising and lowering the holders comprising a cylinder located between the tanks, its 75 piston forming the sole support for the article holders, means for controlling the admission and escape of the fluid to and from the opposite sides of the piston and means for accurately adjusting the position of the 80 cylinder with respect to the tanks and holding it in such position.

In testimony that we claim the foregoing as our invention, we have signed our names in presence of two witnesses, this sixteenth 85 day of March, 1908.

REME A. BEAUSEJOUR.
GUSTAV DRUBEL.
